DESIGN FOR A GAME BOARD

John Scarne, Fairview, N. J.

Application July 29, 1946, Serial No. 132,080

Term of patent 14 years

(Cl. D34—5)

To all whom it may concern:

Be it known that I, John Scarne, a citizen of the United States of America, residing in the city of Fairview, county of Bergen, and State of New Jersey, have invented a new, original, and ornamental Design for a Game Board, of which the following is a specification, reference being had to the accompanying drawing, forming a part thereof.

The figure is a view in perspective of a game board, showing my new design.

I claim:

The ornamental design for a game board, as shown.

JOHN SCARNE.
